EDWIN R. GILL, OF YONKERS, NEW YORK, ASSIGNOR, BY MESNE ASSIGNMENTS, TO
HALL SWITCH & SIGNAL COMPANY, A CORPORATION OF MAINE.

SIGNALING SYSTEM.

1,070,371.

Specification of Letters Patent. Patented Aug. 12, 1913.

Application filed July 27, 1909. Serial No. 509,932.

To all whom it may concern:

Be it known that I, EDWIN R. GILL, a citizen of the United States, residing in the city of Yonkers, county of Westchester, and 5 State of New York, have invented a certain new and useful Improvement in Signaling Systems, of which the following is a specification.

This invention relates to signaling systems, and more particularly to such systems as are adapted to railroad and train despatching.

One of the objects of the invention is to provide improved means whereby train despatching messages and messages independent thereof may be transmitted by different operators without interference, over a single line wire, and whereby the train despatcher will be able at any time to take possession of 20 the line.

Another object is to provide improved means whereby signaling impulses may be impressed upon the line without interfering with the voice currents, thereby permitting 25 of a simultaneous use of the line for telephoning or signaling.

A further object is to provide improved means in a signaling system of the above character whereby in each station a plurality 30 of signals of different characteristics may be operated through the employment of a single selective calling apparatus.

Other objects will be in part obvious and in part pointed out hereinafter.

35 The invention accordingly consists in the features of construction, combinations of elements and arrangement of parts, which will be exemplified in the construction hereinafter described, and the scope of the application of which will be indicated in the following claims.

In the accompanying drawing which is to be taken as a part of this specification and in which I have shown schematically a 45 merely preferred form of embodiment of the invention, the figure represents a telephone line having included therein selectively operated signaling devices together with types of the adjuncts essential to a successful 50 achievement of the objects premised.

Referring now to the drawing: The line is

indicated at 1, and 2 and 3, respectively, indicate batteries; said batteries being arranged with their corresponding poles oppositely connected in the line, as shown. Arranged within the train despatcher's station, which is indicated at A in the drawings, are relays 4 and 5 respectively, said relays being operated by local circuits 6 and 7, having sources of current supply as batteries 8 and 10 respectively. Connected in these local circuits are sender keys 11 and 12, which when operated cause the relays to send impulses of a predetermined character over the line wire thereby to operate selector means as at 13, connected in a bridge 14 of the line. These sender keys will preferably be of the type shown and described in my co-pending application, Serial No. 451,663. Although various types of selector apparatus may be employed in this relation, I 70 preferably employ an instrument of a kind disclosed in Letters Patent 906,523, granted to me December 15th, 1908. This selector includes a magnet 15 and a coil 16 on said 75 magnet, the latter being connected with the terminal 17 of a local signal operating circuit and with a terminal 18 to which in turn is connected a contact member 20 with which co-operates a circuit closer 21, forming a part 80 of the selector apparatus.

22 indicates a device in the nature of a polarized relay, the coils of which are connected in bridge 14 of the line, and an armature 23 of this relay is adapted to engage 85 with contacts 24 and 25 of the signaling circuits, for a purpose hereinafter to be described.

26 and 27 indicate signals which in the present instance are shown as being constituted by ordinary electric bells. These 90 bells are differently toned so that they may be readily distinguished, or if desired, for one of these signals may be substituted an ordinary buzzer. In the present embodiment of the invention, the different characteristics of the signals have been indicated by a difference in form of the sound producing parts 28 and 30.

31 indicates a battery from which leads a 100 wire 32, and from the latter leads a wire 33 to the terminal 34 of signal 27. From

- the opposite terminal 35 of this signal leads a wire 36 to the contact 25. Wire 37 leads from wire 32 to the terminal 38 of signal 26, and from opposite terminal 40 of said signal leads a wire 41 to contact 24. Armature 23 of the relay is connected with terminal 17 of the selective device by a wire 42 and a wire 43 leads from terminal 18 to the battery 31. It will thus be seen that both of the signals 26 and 27 are connected in local circuits, and that either circuit may be closed by the circuit closer 21 engaging the contact 20, the particular circuit closed depending upon the position of armature 23 with respect to the contact points 24 and 25, respectively. As shown in the drawings when armature 23 is in engagement with contact 25, the following circuit is established when circuit closer 21, engages contact 20. From battery 31 through wires 32 and 33 to signal 27 thence through wire 36, contact point 25, armature 23, wire 42, coil 16, circuit closer 21, contact 20, and wire 43 to battery 31.
- When the armature 23 is in engagement with contact 24 the following circuit is established: from battery 31 through wires 32 and 37 to signal 26 thence through wire 41, contact point 24, armature 23, wire 42, coil 16, circuit closer 21, contact 20 and wire 43, back to battery. Thus it will be seen that either of signals 26 or 27 may be independently operated, the particular signal operated being dependent upon the position of the armature 23 with respect to the contacts with which it co-operates as stated above.
- 44 and 45 respectively indicate telephones connected in bridges 46 and 47 of the main line, condensers as at 48 and 50 being provided in said bridges. Telephone 44 is shown as being located in the despatcher's station A, and telephone 45 in the receiver's station B. It will be understood that stations similar to B may be located at various points along the main line.
- In order to provide means whereby batteries 2 and 3 may be applied to or withdrawn from the line in such manner that no audible effect will be produced on the telephones in bridge thereof, I employ devices for slowing down the rates at which the battery currents rise and fall; said devices in the present instance comprising retardation coils 51 and 52, respectively, a condenser being provided at 53.
- In order to actuate the armature 23 of the polarized relay whereby either of the local signal operating circuits previously described may be closed by the engagement of the armature with either of contacts 24 or 25, means is provided for reversing the direction of flow of current in the main line, such result being attained by cutting-in either of the batteries 2 or 3, which as above

indicated have their corresponding poles oppositely connected in the line. The means for attaining these ends comprise devices in the nature of polarized relays 54 and 55, respectively. Armature 56 of relay 54 is adapted to engage a contact 57 leading to the negative side of battery 2 and the armature 58 of relay 55 is adapted to engage with contact 60 leading from the positive side of the battery 3. A wire 61 leads from the frame of the relay 55 which is in electrical contact with the armature 58 to the contact 62 with which co-operates the armature 63 of the relay 5, so that when armature 58 is in a position, as shown, the following circuit is established in the main line. From battery 3 to contact 60, armature 58, through the frame of the relay, wire 61, contact 62, armature 63, to the main line, thence through the polarized relays and selective apparatuses connected in bridge of the line to the negative side thereof back to battery 3.

When armature 56 of relay 54 is in engagement with contact 57, armature 58 being removed from contact 60 as will herein-after be described, the following circuit is established: from battery 2 to the main line, then through the various polarized relays and selective apparatuses in bridge thereof to the negative side of the line, then through armature 64 of relay 4, contact 65, wire 66 to the frame of the relay 54, armature 56, contact 57, back to battery. It will be understood of course that in each of the circuits above described, it is presumed that the relays in the despatcher's station have been operated respectively by the sender keys 12 and 11. This reversal of the current in the main line as above described sets the various armatures of the polarized relays along the main line in proper positions to operate the desired signal when the selective apparatus at the station to be called has closed the local circuit. It will be noted that the position of the armature 23 is dependent upon the particular relay 54 and 55 which is operated.

Relays 54 and 55 are operated by means of local circuits which will now be described. 67 indicates a battery which furnishes the current supply to the circuits which operate the relays 54 and 55 respectively. 68 indicates a switch which herein may be termed "despatcher's switch" and 69 indicates a similar switch which may be termed "message man's switch". Supposing switch 68 to be closed the following circuit is established, from battery 67 through wire 70, through coils of the relay 54, wire 71, wire 72, lamp 73, wire 74, switch arm 75, wire 76, thence through the coils of the relay 55, and wire 77, back to battery. The provision of the lamp 73 of this circuit operates to inform the "message" man who operates the switch 130

69 that the "despatcher's switch" is closed and that the line is in use. It will be understood that the relays are so arranged that when the circuit above described is closed 5 the armatures 56 and 58 will occupy the position shown in the drawings, the battery 3 being applied to the main line.

78 indicates a switch which may be termed "despatcher's cut-out switch". This switch 10 is normally closed so that when the "despatcher's switch" is open and the "message man's switch" closed, the following circuit is established: from battery 67 through wire 70 and the coils of relay 54, wire 71, wire 80, 15 through the switch arm 81 of switch 69, wire 82, switch arm 83 of switch 78, wire 84, lamp 85, wire 86, wire 76, thence through the coils of the relay 55 and wire 77, back to battery. The provision of the lamp 85 in this circuit 20 operates to inform the despatcher that the "message man's switch" is closed and the wire in use, and it will be understood that when this last described circuit is closed the armatures 56 and 58 are in such positions 25 that the armature 58 and contact 60 are out of engagement, the battery 3 being removed from the line and the battery 2 cut into the line. Each of armatures 56 and 58 have arms to which may be attached colored disks 30 or other visual indicating members.

Having thus described my improved signaling system the operation, which, to a large extent should be obvious, may now be understood.

35 Assuming switch 68 to be closed and switch 69 open, thereby applying battery 3 to the line, the operation of the sender key 12 will by means of the relay 5 send the proper combination of impulses to the main 40 line to operate the selective apparatus in the station, which it is desired to call and, with the arrangement of the parts shown in the present drawings the operation of the sender key 12 will serve to operatively connect the 45 signal 27 with its source of current supply. Assuming however, the switch 68 to be open and the switches 69 and 78 closed the operation of the sender key 11 will apply the battery 2 to the line thereby reversing the direction of current flow therein, whereby the armature 23 will contact with the contact 24 thereby closing a circuit through the signal 50 26 and opening the circuit through the signal 27.

55 It will be understood that when either of the ringing circuits is closed by the operation of the selector apparatus in combination with the armature 23 of the polarized relay, the interrupted current set up in said 60 circuit by the vibration of the bell armature passing through the coil 16 which acts as a primary, induces a current in the main line, which current acting upon the telephone apparatus connected in bridge thereof causes a 65 buzzing in the telephone being used, inform-

ing the operator that the particular station desired has been called.

In the present embodiment of the invention, the coil of the selector operates as an impedance thereby preventing such an interference with the telephone apparatus connected in bridge of the line by the signaling impulses sent thereover, as would tend to interfere with said voice currents.

It will accordingly be seen that I have 75 provided a signaling system of simple yet efficient operation. A single selective apparatus in each of the various stations along the main line serves to close circuits in a plurality of signaling devices of different characteristics; thereby when the signal is operated the particular operator desired is at once notified. The provision of the switch 78 in the message man's circuit, said switch being preferably located in proximity to the 80 despatcher's circuit, enables the latter at all times to take command of the wire providing he deems it necessary in the performance of his duties as train despatcher.

As many changes could be made in the 85 above construction and many apparently widely different embodiments of this invention could be made without departing from the scope thereof, it is intended that all matter contained in the above description or 90 shown in the accompanying drawing shall be interpreted as illustrative and not in a limiting sense.

It is also to be understood that the language used in the following claims is intended to cover all of the generic and specific features of the invention herein described and all statements of the scope of the invention, which as a matter of language, might be said to fall therebetween.

Having described my invention, what I claim as new and desire to secure by Letters Patent is:

1. In a signaling circuit, a main line, selective apparatus in bridge of said line, a 110 plurality of local circuits, a normally open switch common to each of said local circuits adapted to be closed by said selective apparatus, a signaling device in each local circuit, and means in bridge of said line for 115 closing one of said local circuits to the exclusion of the other.

2. In a signaling circuit, a main line, selective apparatus in bridge of said line, a 120 plurality of local circuits each of which includes a signal, a source of current supply common to each of said local circuits, a normally open switch common to both of said circuits adapted to be closed by said selective apparatus, and means in bridge 125 of said main line for closing either of said circuits to the exclusion of the other.

3. In a signaling system, a main line, selective apparatus connected in bridge of said line, a plurality of electrically operated sig- 130

nals, a switch in electric connection with both of said signals, said switch being adapted to be operated by said selective apparatus, and means connected in said bridge 3 adapted, when said switch is closed, to selectively operate one of said signals.

4. In a signaling system, a main line, selective apparatus connected in bridge of said line, a plurality of independent electrically 10 operated signals, a source of electric supply common to both of said signals, a normally open switch in electrical connection with both of said signals, and means connected in bridge of the line adapted, when said 15 switch is closed by said selective device, to selectively operate one of said signals.

5. In a signaling system, a main line, selective apparatus in bridge of said line, a plurality of electrically operated signals, a 20 normally open switch in electric connection with both of said signals, a source of current supply common to both of said signals, said switch being adapted to be closed by said selective apparatus, and a relay 25 connected in bridge of the line adapted to selectively operate one of said signals.

6. In a signaling system, a main line, selective apparatus in bridge of said line, a plurality of electrically operated signals 30 having different characteristics, a normally open switch electrically connected to both of said signals, said switch being adapted to be closed by said selective apparatus, and means in bridge of the line adapted to 35 selectively operate one of said signals in accordance with the direction of flow of current in said main line.

7. In a signaling system, a main line, means for impressing current in opposite 40 directions upon said line, selective apparatus in bridge of said line, a plurality of electrically operated signals having different characteristics, a normally open switch in electrical connection with both of said signals 45 adapted to be closed by said selective apparatus, and means in said bridge for selectively operating one of said signals in accordance with the direction of flow of current in the main line.

50 8. In a signaling system, a main line, a plurality of current supplying devices each of which is adapted to impress a flow of current in a different direction upon said line, selective apparatus connected in bridge 55 of the line, a plurality of electrically operated signals having different characteristics, a normally open switch in electrical connection with both of said signals, a source of current supply for said signals, 60 and means in said bridge whose operation is determined by the direction of flow of current in the main line for connecting one of said signals with its source of current supply to the exclusion of the other.

65 9. In a signaling system, a main line, a

plurality of current supplying devices the corresponding poles of which are oppositely connected to said main line, means for connecting either of said current supplying devices with said main line, selective apparatus in bridge of said line, a plurality of electrically operated signals having different characteristics, a normally open switch in electrical connection with both of said signals which is adapted to be closed by said selective apparatus, and means in bridge of the line whose operation is determined by the particular current supplying device connected in the main line for connecting one of said signals with its source of current supply. 70 75 80

10. In a signaling system, a main line, a pair of current supplying devices, corresponding poles of which are adapted to be oppositely connected to said line, means for connecting either of said current supplying devices with said line, a plurality of electrically operated signals having different characteristics, a local circuit for each of said signals, a normally open switch common to both of said local circuits adapted to be closed by said selective apparatus, and a polarized relay for rendering either of said signals operative. 85 90

11. In a signaling system, a main line, a pair of batteries corresponding poles of which are oppositely connected in the main line, a pair of relays each of which is adapted to connect one of said batteries to the line, selective apparatus connected in bridge 100 of the line, a pair of signals, said signals having different characteristics, a normally open switch electrically connected with both of said signals, means in bridge of the line for selectively operating said switch, and 105 means in bridge of the line for selectively determining the operation of said signals. 95

12. In a signaling system, a main line, a pair of batteries corresponding poles of which are adapted to be oppositely connected in said line, a pair of relays each of which when operated is adapted to apply one of said batteries to the line, means for operating each of said relays, means for visually indicating which of said relays has 115 been operated, a pair of independent signals, selective apparatus in bridge of the line, a normally open switch in electrical connection with both of said signals which is adapted to be closed by said selective apparatus, a source of current supply common to both of said signals, and means in said bridge for connecting one of said signals with said source of current supply when said switch has been closed by the selective 120 apparatus, the particular signal so connected being determined by the particular relay operated. 125

13. In a signaling system, a main line, a pair of batteries corresponding poles of 130

which are adapted to be oppositely connected in the line, a pair of local circuits, a relay in each local circuit adapted when operated to apply one of said batteries to the line, means for closing either of said local circuits, means for indicating to the operator of one of said relays that the operator of the other relay has applied a battery to the line, selective apparatus in bridge of the line, a plurality of electrically operated signals having different characteristics, a normally open switch adapted to be closed by said selective apparatus, said switch being electrically connected with both of said signals, a common source of current supply for both the signals, and means in bridge of the line whose operation is determined by the particular relay operated for connecting one of said signals with its source of current supply.

14. In a signaling system, a main line, a plurality of signals having different characteristics, a plurality of local circuits, a switch common to each of said local circuits, selective means for closing said switch, a second switch in each of said local circuits, and a polarized relay in bridge of the line for operating either of said last named switches to the exclusion of the other.

15. In a signaling system, a main line, selective apparatus in bridge of the line, a plurality of electrically operated signals, means in bridge of said main line adapted to determine the operation of one of said signals in accordance with the direction of flow of current in the main line, and means for reversing the direction of flow of current in said line.

16. In a signaling system, a main line, selective apparatus in bridge in the line, a plurality of electrically operated signals, means in bridge of said main line adapted to determine the operation of one of said signals in accordance with the direction of flow of current in said main line, and a plurality of independently operated relays adapted to reverse the direction of current in said main line.

17. In a signaling system, a main line, selective apparatus in bridge of the line, a plurality of electrically operated signals, means in bridge of the main line adapted to selectively operate one of said signals in accordance with the flow of current in said main line, a plurality of sources of current for said main line, and a plurality of independently operated relays each of which is adapted to connect one of said sources of current with said main line.

18. In a signaling system, a main line, selective apparatus in bridge of the line, a plurality of electrically operated signals, means in bridge of said main line adapted to selectively operate one of said signals in

accordance with the direction of flow of current in said main line, a plurality of batteries corresponding poles of which may be oppositely connected in the main line, and a plurality of independently operated relays, each of which is adapted to connect one of said batteries with the main line, whereby the direction of flow of current may be reversed therein.

19. In a signaling system, a main line, selective apparatus in bridge of the line, a plurality of electrically operated signals, means in bridge of said main line adapted in conjunction with said selective means to selectively operate one of said signals in accordance with the direction of flow of current in the main line, a pair of batteries, each of which is adapted to impress current upon the main line in a direction opposite to that in which it is impressed by the other battery, and a relay for connecting the main line with either of said batteries.

20. In a signaling system, a main line, selective apparatus in bridge of the line, a plurality of electrically operated signals, means in bridge of the main line adapted to selectively operate one of said signals in accordance with the direction of flow of current in the main line, a pair of batteries each of which is adapted to impress a current upon the main line in a direction opposite to that in which it is impressed by the other thereof, a relay for connecting either of said batteries with the main line whereby the direction of flow of current therein may be reversed, and a circuit closer for each of said relays.

21. In a signaling system, a main line, selective apparatus in bridge of the line, a pair of electrically operated signals, means in bridge of the line adapted in conjunction with said selective means to determine the operation of one of said signals to the exclusion of the other, a pair of batteries, each of which is adapted to impress a flow of current upon the main line in a direction opposite to that in which it may be impressed by the other battery, a relay for each of said batteries adapted to connect the same with the main line, a switch for closing the circuit of each of said relays, and a switch located in proximity to one of said first mentioned switches for opening the circuit closed by the other switch.

22. In a signaling system, in combination a main line, telephonic apparatus in bridge of the line, selective means in bridge of the line, a pair of electrically operated signals, means in bridge of the line adapted in conjunction with said selective means for reversing the flow of current in the main line, a pair of batteries each of which is adapted to impress current on the main line in a

direction opposite to that in which it is impressed by the other battery, an independently operated relay for connecting each of said batteries with the main line, a switch 5 for closing the circuit of each of said relays, and a switch located in proximity with one of the switches for opening the circuit closed by the other switch.

23. In a signaling system, in combination 10 a main line, telephonic apparatus in bridge of the line, conductance and impedance in bridge of the line, selective apparatus in bridge of the line, a plurality of independently operated signals, means in bridge of the line adapted in combination with said 15 selective apparatus to determine the operation of one of said signals to the exclusion of the other, a pair of batteries each of which is adapted to impress a flow of current upon the main line in a direction opposite to that in which it is impressed by the other, an independently operated relay for each of said batteries, each relay being adapted to connect its battery with the main 20 line, a switch for closing the circuit of each of said relays for indicating to the operator of one switch that the switch controlled by the other operator is closed.

24. In a signaling system, in combination, 30 a main line, telephonic apparatus in bridge of the line, conductance and impedance in bridge of the line, selective apparatus in bridge of the line, a plurality of independently operated signals, means in bridge of the line adapted in conjunction with said 35 selective apparatus to determine the operation of one of said signals, a pair of batteries each of which is adapted to impress a flow of current upon the main line in a direction opposite to that in which it is impressed by the other, an independently operated relay for each of said batteries, each relay being adapted to connect its battery to the main line, a switch for closing the 40 circuit of each of said relays, means in the circuit of each of said relays of indicating to the operator of each switch that the switch controlled by the other operator is closed, and a switch located in proximity to 45 one of said first mentioned switches for opening the circuit which is adapted to be closed by the other switch.

25. A selective signaling system comprising 55 a signal-sending station, and a plurality of signal-receiving stations, a signal circuit-controlling device at each signal-receiving station, two signals under the control of each device, an auxiliary signal circuit-controlling element having a circuit controlling 60 contact for each associated signal, and means for operating either one of said two signals with a given position of their associated device, said means including a source of current at the signal-sending station, and

means for reversing the polarity of the current supplied to said signal-receiving stations. 65

26. A selective signaling system comprising 70 a signal-sending station and a plurality of signal-receiving stations, a signal circuit-controlling device at each signal receiving station, two signals under the control of each device, means for setting said device, and means for operating either one of its associated two signals with a given position 75 of said device, said means including a source of current at the signal-sending station, and means for reversing the polarity of the current supplied to said signal-receiving stations. 80

27. A selective signaling system comprising 85 a signal-sending station and a plurality of signal-receiving stations, a signal circuit-controlling device at each signal-receiving station, two signals under the control of each device, means for setting said device, an auxiliary signal circuit-controlling element having a circuit controlling contact for each associated signal, and means for operating either one of said two signals 90 with a given position of their associated device, said means including a source of current at the signal-sending station, and means for reversing the polarity of the current supplied to said signal-receiving stations. 95

28. A selective signaling system comprising 100 a signal-sending station and a plurality of signal-receiving stations, a signal circuit-controlling device at each signal-receiving station, two signals under the control of each device, an auxiliary polarized signal circuit controlling element having a circuit controlling contact for each associated signal, and means for operating either one of 105 two signals with a given position of their associated device, said means including a source of current at the signal-sending station, and means for reversing the polarity of the current supplied to said signal-receiving stations. 110

29. A selective signaling system comprising 115 a signal sending station and a plurality of signal receiving stations, a step-by-step signal circuit controlling device at each signal receiving station, two signals under the control of each device, and means for operating either one of two signals with a given position of their associated device, said means including a source of current at the signal sending station, and means for reversing the polarity of the current supplied to said signal receiving stations. 120

30. A selective signaling system comprising 125 a signal sending station and a plurality of signal receiving stations, a signal circuit controlling device at each signal receiving station, two signals under the control of

each device, and means for operating either one of two signals with a given position of their associated device, said means including a source of current at the signal sending station, and means for reversing the polarity of the current supplied to said signal receiving stations.

In testimony whereof I affix my signature in the presence of two witnesses.

EDWIN R. GILL.
